UNITED STATES PATENT OFFICE.

McCLELLAN B. KRAFT, OF SPRING GROVE, PENNSYLVANIA.

FLEXIBLE COUPLING.

Application filed January 25, 1922. Serial No. 531,754.

To all whom it may concern:

Be it known that I, McCLELLAN B. KRAFT, a citizen of the United States, residing at Spring Grove, in the county of York and State of Pennsylvania, have invented new and useful Improvements in Flexible Couplings, of which the following is a specification.

This invention relates to smoke conductors for locomotives.

The particular object of this invention is to provide a universal, flexible, compressible and expansible coupling, which is substantially tight or smoke proof, durable, and wherein the construction is relatively cheap and simple.

This invention will be more fully understood from the following description, taken in connection with the accompanying drawings, forming a part hereof, and in which similar numerals refer to similar parts throughout the several views.

Fig. 1, represents a passenger train with a smoke conductor, and shows the adaptability of the coupling which forms the subject matter of this invention.

Fig. 2, is a longitudinal sectional view of the coupling.

Fig. 3, is an end view of Fig. 2.

Fig. 4, is a detail drawing showing one form of construction in which the coupling may be connected to a locomotive stack.

Referring to the drawings, 1 is a smoke conductor consisting of a tube which runs the entire length of the train and is divided into sections 6, 7, 8, and 9; section 6 being secured to the top of the locomotive through the straps 10, section 7 to the tender through the brackets 11, section 8 to the top of the coach through the straps 12, and section 9 being carried by the smoke box 4.

The end of each section of the smoke conductor 1 is provided with a coupling 2, the details of which are fully shown in Fig. 2. The coupling 2 is made up of sections 14, 15, 16 and 17, each of which are crimped to interlock with each other as shown at 18, 19, and 20. The crimped joints 18, 19, and 20 are provided with enough freedom or space as shown at 21 to permit flexion in any direction.

The springs 22 normally hold the coupling in a straight line position as shown in Fig. 2, through the flanges 43.

Free to slide in the end of the section 17 is a tube 23 which is riveted to the flange 24

as shown. A shell 25 is fitted free to slide over the outside of the section 17; this shell is also riveted to the flange 24 as shown. The ends of the shell 25 and the section 17 are bent over to form flanges as shown at 26 and 27 respectively, and springs 28 are interposed to normally hold the flange 24 in firm contact with a corresponding flange 24 of another section, such a flange being shown in light broken lines Fig. 2. A face plate 29 is riveted to the flange 24 and substantially forms a part thereof.

A yoke 30 is riveted to the inside of the tube 23 through the flanges 31; the object of this yoke being to guide or pilot the tubes while they are butting together and hold them in true alignment with each other. It will be observed in Fig. 2 that these yokes enter the abutting tubes, the one shown in full lines projecting into the tube shown in light broken lines, and the yoke shown in light broken lines projecting into the tube shown in full lines.

The yoke 30 is located centrally in the tube as shown in full lines Fig. 3. The yoke of a corresponding tube takes a position either to the right or left of this yoke, the right hand position being shown in light broken lines at 30°. The face plate 29 is provided with lugs 32 which holds the yokes in close relation, thereby holding the coupling in substantially true alignment.

It is apparent from the above description that the flexible coupling shown in Fig. 2, provides a joint between the various sections of the smoke conductor 1, which will accommodate the opposite movement of the various units of the train within the necessary limits.

For the best results it is obvious that all the couplings 2 should be of the proper length so that the joint is made directly over the coupling of the train units. For instance, the joint between the sections 7 and 8 of the smoke conductor is made directly over the coupling 33 between the tender 34 and passenger coach 35. The same condition should also exist between the locomotive 36 and the tender 34.

The smoke box 4 forms a T connection between the locomotive stack 37 and the smoke conductor 1, and as shown in the drawing consists principally of a square casing which opens into the sections 6 and 9 of the smoke conductor and the stack 37.

When two locomotives are employed to

draw the train, the smoke conductor of the first locomotive connects with the coupling 2 at the end 49; the end of the tender of the first locomotive being shown in light broken lines at 50.

It is obvious that any number of coaches may be coupled to the train and the tubes of each individual coach will connect end for end, thereby continuing the length of 16 the smoke conductor 1 to the end of the train. A second coach is shown in light broken lines at 61.

Having thus described my invention, what I claim and desire to secure by United States 15 Letters Patent is as follows:

1. A flexible half coupling comprising a series of interlocking ring shaped sections, a piloting yoke, substantially as shown and described, fixed to one end of said series 20 of ring shaped sections, and a series of contractile springs arranged around the outside of said ring shaped sections, the opposite ends of each spring being connected to the respective end ring shaped sections of said 25 series.

2. A flexible half coupling comprising a main tubular section, a larger tube adapted to slide over said main tubular section, resilient means normally holding said larger 30 tube in a forward position relative to said main tubular section, a flange fixed to said larger tube, and a smaller tube fixed to said flange and adapted to slide within said main tubular section.

3. A flexible half coupling comprising a flexible tubular section, a slidable flange sec-

tion, a piloting yoke protruding from said flange section, and lugs carried by said flange which form a notch on each side of said yoke of such depth and width which will receive a similar yoke carried by a companion half coupling.

4. A flexible half coupling comprising a series of interlocking ring shaped sections, a main tubular section interlocking with one 45 end of said series of ring shaped sections, a short tube interlocking with the opposite end of said series of ring shaped sections, a series of contractile springs, the opposite 50 ends of each spring being connected respectively to said main tubular section and said short tube, an outwardly extending flange formed on the free end of said short tube, a larger tube adapted to slide over said short tube including said flange, an inwardly 55 extending flange formed on the end of said larger tube, a second series of contractile springs, the opposite ends of each being respectively fixed to said inwardly and outwardly extending flanges, a ring fixed to 60 the free end of said larger tube and forming a flange, a smaller tube fixed to said ring and adapted to slide within said short tube, a piloting yoke protruding from said smaller 65 tube beyond said ring, and lugs carried by said ring and adapted to form a notch on each side of said yoke of such depth and width as will receive a similar yoke carried by a companion half coupling.

In testimony whereof I affix my signature.

McCLELLAN B. KRAFT.
